(57) **CLAIM**

We claim the ornamental design for a vehicle front bumper cover, as shown and described.

DESCRIPTION

FIG. 1 is a right side front perspective view of a right vehicle front bumper cover, the left vehicle front bumper cover (not shown) is a mirror of the right vehicle front bumper cover; FIG. 2 is a front elevational view of the vehicle front bumper cover;

FIG. 3 is a right side elevational view of the vehicle front bumper cover;

FIG. 4 is a left side elevational view of the vehicle front bumper cover;

FIG. 5 is a top plan view of the vehicle front bumper cover; and,

FIG. 6 is a bottom plan view of the vehicle front bumper cover.

Shading is used to illustrate the curvature of the part and not color.
